Primary Examiner — Jeffrey D Asch*Assistant Examiner* — Rebekah A Caruso(74) *Attorney, Agent, or Firm* — Westbridge IP LLC(57) **CLAIM**

The ornamental design for a multimedia communication terminal, as shown and described.

DESCRIPTION

FIG. 1 is a front elevational view of a multimedia communication terminal showing our new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a front, right and top side perspective view thereof;

FIG. 8 is an enlarged view of a portion 8 in FIG. 1;

FIG. 9 is an enlarged view of a portion 9 in FIG. 7; and,

FIG. 10 is an enlarged view of a portion 10 in FIG. 7.

The evenly broken lines in the drawings illustrate portions of the article that form no part of the claim.

1 Claim, 10 Drawing Sheets
